UNITED STATES PATENT OFFICE.

WINTHROP PARKER, OF MANCHESTER, NEW HAMPSHIRE.

SPINNING AND TWISTING MACHINE.

1,147,042.

Specification of Letters Patent. Patented July 20, 1915.

Application filed October 30, 1914. Serial No. 869,479.

To all whom it may concern:

Be it known that I, WINTHROP PARKER, a citizen of the United States, residing at Manchester, county of Hillsboro, and State 5 of New Hampshire, have invented an Improvement in Spinning and Twisting Machines, of which the following description, in connection with the accompanying drawing, is a specification, like characters on the 10 drawing representing like parts.

This invention relates to spinning and twisting machines of that type which are constructed to lay on the yarn receiver first a preliminary winding and then a main or 15 service winding, and the principal object of the invention is to provide a machine of this type with means for actuating the ring rail to lay the preliminary winding which is separate and independent from the 20 usual builder motion by which the main or service winding is laid, and which is provided with means for automatically rendering the preliminary winding mechanism inoperative after the preliminary winding has 25 been laid whereby the regular builder motion will come into play automatically after the preliminary winding has been laid to lay the main or service winding on the yarn receiver.

30 Further objects of the invention are to provide a machine of the above type with means for laying the preliminary winding on the yarn receiver which are capable of adjustment so as to provide for varying the 35 size of the preliminary winding and its position on the bobbin or yarn receiver, and otherwise to improve spinning or twisting machines of the above type, all as will be more fully hereinafter described.

40 In order to give an understanding of the invention I have illustrated herein some selected embodiments thereof which will now be described, after which the novel features of the invention will be pointed out in the 45 appended claims.

In the drawings, Figure 1 is a partial view of a spinning and twisting machine showing my improvements applied thereto; Fig. 2 is a detail plan view of the mechanism shown in Fig. 1 for disengaging the 50 preliminary winding mechanism at the completion of the preliminary winding; Fig. 3 is a side elevation of a different form of disengaging means; Fig. 4 is a section

on the line $x-x$, Fig. 2; Fig. 5 is a section 55 on the line $y-y$, Fig. 2. Fig. 6 is a view of the bobbin showing the preliminary winding thereon.

The portion of the spinning or twisting frame herein shown comprises the head or 60 end frame 1, the spindle rail or frame 2 in which the spindles or other yarn receivers 3 are rotatively mounted, and the ring rail 4 carrying the spinning rings. This ring rail 4 is capable of a vertical traversing movement 65 to lay the yarn on the yarn receivers as usual, and the device herein illustrated includes the ordinary builder motion for giving a traversing movement to the ring rail, said builder motion operating to give 70 the traversing motion necessary to lay the main or service winding on the yarn receiver. The builder motion herein illustrated is of the usual type comprising a builder arm which is actuated by a cam 75 member and is connected by a builder chain with a rocker, which in turn actuates the ring rail 4 through lifter rods. This rocker is shown at 5, it being pivoted to the frame at 6 and it has engagement with the lifter 80 rod 7 secured to the ring rail 4. The rocker 5 is connected to the usual builder chain 8 which leads to the builder arm 9. This builder arm is given a constant stroke through a rotatable cam member 10, as usual, thereby 85 to cause the ring rail 4 to have its traversing movement. As the builder arm rotates, the builder chain 8 is gradually let off or lengthened through the operation of the pick-pawl 11 and pick-wheel 12, thereby 90 to give to the ring rail the required "gain" as the yarn is laid on the yarn receiver. Inasmuch as the parts above described are such as are commonly found in spinning or 95 twisting machines, I do not deem it necessary to further describe them.

In winding yarn on a yarn receiver, it is often desirable to lay on the yarn receiver first a preliminary winding, and then a main or service winding. This preliminary winding is sometimes used as a so-called "bunch" 100 to coöperate with the feeler of a filling-replenishing loom for the purpose of causing filling replenishment upon substantial exhaustion of the filling, and it is sometimes 105 used merely to provide a sufficient length of yarn to constitute one or two picks so that filling replenishment will take place before

the yarn is entirely exhausted from the yarn receiver. My invention provides a novel mechanism for giving the ring rail 4 a traversing movement to lay the preliminary windings on the yarn receivers before the main or service winding is laid, which means is independent from the builder motion above described and is rendered inoperative automatically upon the completion of the preliminary winding. This independent mechanism for giving the ring rail 4 the traversing movement necessary to lay the preliminary winding may be operated from any suitable source of power, and in the illustrated embodiment of the invention I have chosen to actuate it from the gearing in the head or end 1 of the frame, preferably from the front top roll. This independent mechanism, which I will herein-after refer to as the "preliminary winding mechanism" is herein illustrated as comprising a reciprocatory actuator 13 operated through an instrumentality independent from that which actuates the builder motion and adapted to be connected to or disconnected from the ring rail 4 independently of the regular builder motion. I find it convenient to effect the connection of the actuator 13 with the ring rail 4 through the rocker member 5, although this particular construction is not essential to the invention. I also find it convenient to give the actuator 13 its reciprocatory movement from the front top roll, this being the construction herein shown. The actuator 13 is in the form of a bar which is connected at one end to a crank pin 14 carried by a crank member 15 that is rotatably mounted in suitable bearings in the frame. The eccentricity of the pin 14 relative to the axis of the crank member 15 serves to determine the length of traverse of the preliminary winding mechanism. This member 15 is driven from the gearing constituting the head of the machine, preferably from the front top roll, and for this purpose said member 15 is in the form of a bevel gear which meshes with a bevel gear 16 carried on a shaft 17 that in turn is driven from the shaft 18 of the front top roll through intermeshing gears 19. This particular form of gearing is, however, only illustrative of one method of giving reciprocatory movement to the actuator 13. The actuator 13 is thus a constantly-moving actuator having a constant reciprocatory movement. As stated above, I find it convenient to provide for the connection of the actuator 13 with the ring rail 4 through the rocker member 5, and for this purpose I have shown the rocker member as provided with the finger or arm 20 which is adapted to engage in a recess or notch 21 formed in the actuator. When the finger 20 is thus engaged in the recess 21, then reciprocatory movement of the actuator 13 will rock the

rocker 5 thereby raising and lowering the ring rail 4. This traversing movement of the ring rail 4 which is effected by the actuator 13 is the movement which lays on each yarn receiver 3 its preliminary winding. The movement which is given to the ring rail 4 by the actuator 13 is not interfered with by the operation of the ordinary builder motion, for the vibratory movement of the builder arm 9 will simply place more or less slack in the chain 8.

While the actuator 13 may be given a reciprocatory movement at any desired speed, I will preferably so operate said actuator as to give the ring rail 4 a comparatively rapid traverse so that the preliminary winding which is shown at 22 in Fig. 6 will be laid with a coarse pitch. The advantage of this is that the bobbin can be more readily stripped of the remnant of yarn left thereon after it is discharged from a filling-replenishing loom than if said remnant of yarn were laid with the coils thereof tightly together, and any desired size of bunch can be made with less yarn, thereby reducing the amount of waste yarn left on the bobbin after it is discharged from a filling-replenishing loom.

My invention also comprehends means for automatically disengaging the actuator 13 from operative connection with the ring rail when the preliminary winding is completed so that thereafter the builder motion will come into play automatically to lay on the yarn receiver the main or service winding. This automatic disconnection of the actuator 13 from the ring rail is herein provided for by a disconnecting device which is adapted to raise the actuator at the proper time so as to disconnect it from the finger 20. This disconnecting member is herein shown in the form of a cam or arm 23 which is mounted on a shaft or stud 24 that is journaled in suitable bearings 25 carried by a bracket or support 26 secured to the frame of the machine. This disconnecting member 23 is normally inoperative, but is actuated to bring it into position to engage the actuator 13 and raise the notch 21 of the latter out of engagement with the finger 20 at the time that the preliminary winding is completed. For this purpose I have herein shown a ratchet wheel 27 which is fast on the shaft 24 and therefore rigid with the disconnecting member 23 and a pick-pawl 28 which is carried by the actuator 13 and is adapted to intermittently advance the ratchet 27 as the actuator vibrates. During the reciprocatory movement of the vibrating actuator 13 the ratchet wheel will be intermittently turned in the direction of the arrow in Fig. 1, and the disengaging member 23 will thus be carried around clockwise, Fig. 1, until it comes into engagement with the actuator 13 and thereby lifts

it out of engagement with the rocker 5. It is desirable that the disengaging movement of the actuator 13 from the arm 20 of the lever should be a quick movement rather than a comparatively slow movement such as would naturally result by the rotary movement of the member 23, and to secure such quick disengaging movement I provide the actuator 13 with a member having a yielding connection therewith, which member is situated to be engaged by the disengaging member 23 as the latter rotates. This yielding member is shown as a pin 29 which is carried by two arms or ears 30 formed on the actuator. The pin projects below the lower ear 30 and has fast thereon a collar 31 between which and the upper ear a spring 32 is confined. As the disengaging member 23 rotates it engages the lower end of the member 29 and will first raise said member against the action of the spring 32 without, however, lifting the actuator. When, however, the spring 32 has been compressed to a sufficient amount, then its tension will overcome the weight of the actuator 13 and the actuator will be given a quick upward movement due to the expansive movement of the spring sufficient to disengage it from the finger 30.

When the actuator 13 has been thus disengaged from the rocker 5, it is necessary to hold it disengaged during the laying of the main or service winding. This end is secured herein by means which render the pick-pawl 28 inactive to further advance the ratchet wheel 27 whenever the actuator 13 is disengaged from the rocker. The pick-pawl herein illustrated is provided with a rearwardly-extending finger 33 and the bracket 26 has rising therefrom a finger 34 provided with a lateral portion 35 which overhangs the finger 33. When the actuator 13 is raised out of engagement with the rocker 5 the finger 33 is brought into engagement with the extension 35 whereby the pawl 28 is rocked about its pivot 36 and thereby disengaged from the wheel 27. This leaves the disengaging member 23 in a position to hold the actuator 13 elevated out of engagement with the rocker arm 5, as will be obvious.

I have also herein provided means whereby when the main or service windings on the yarn receivers have been completed and the bobbins are doffed, the disengaging member 23 may be returned automatically to its initial position thereby permitting the actuator 13 to again engage the rocker for winding the preliminary winding on the fresh bobbins. I accomplish this object herein by the following mechanism: 39 designates a stop pawl pivoted to the bracket 26 at 40 and adapted to engage the ratchet wheel 27, this stop pawl normally preventing back rotation of the ratchet wheel. The

ratchet wheel 27 is acted upon by a spring which normally tends to return it to its initial position whenever the stop pawl 39 is released therefrom. This spring is herein shown at 60 and one end thereof is connected to a hand-wheel 41 fast on the shaft 24, and the other end thereof is connected to the bearing 25 so that as the ratchet 27 is turned in the direction of the arrow, the spring will be wound up. The ratchet member 75 carries a stop pin 42 which is adapted to engage a stop 43 extending from the bracket 26, said stops limiting the return movement of the ratchet 27. The pawl 39 is provided with an extension 44 which is adapted to be engaged by a finger 45 carried on the usual rod 46 which connects the various rockers 5, there usually being several of these rockers on each spinning or twisting machine. When the yarn carriers are filled and it is desired to doff the same, it is customary for the operator to lower the ring rail below the position it normally assumes during its traversing movement in order to carry the spinning rings sufficiently below the bobbins to permit them to be readily doffed. During this movement of the ring rail the rod 46 will be moved to the left, Fig. 1, beyond the position therein shown, during which movement the finger 45 will engage the extension 44 of the pawl 39 and release the pawl from the ratchet 27. When this has been accomplished, the ratchet will return to the position determined by the stops 42, 43 by the action of the spring 40.

The character of the preliminary winding on the bobbin is determined to a considerable extent by the particular form of feeler mechanism in the loom in which the bobbins are to be used, and it is desirable, therefore, to be able to vary the character of the preliminary winding by either varying the size thereof, or the position thereof on the yarn receiver. I provide for varying the position on the yarn receiver by making the actuator 13 adjustable as to its length, this being herein accomplished by making said actuator in two sections which are adjustably connected together by the bolts 47 carried by one member and operating in slots 48 carried by the other member. By adjusting the length of the actuator 13 the position of the rocker 5 and hence of the ring rail 4 relative to the bobbin can be changed, and it is thus possible to place the preliminary winding upon any desired portion of the yarn receiver or bobbin.

To vary the size of the preliminary winding, I provide a construction wherein the stop 42 can be adjusted on the ratchet member 27 so that when the stops are in engagement with each other, the disengaging member 23 may have any desired position. As herein shown the ratchet member 27 is

4
provided with a plurality of apertures 49 into anyone of which the stop 42 may be set, and thus the amount it is necessary to rotate the ratchet 27 in order to bring the member 23 from its initial position into engagement with the member 29 can be adjusted and varied. This provides for laying a greater or less amount of yarn in the preliminary winding.

10 The device shown in Figs. 1 and 2 is especially useful where a preliminary winding containing a comparatively small amount of yarn is required, for at most the actuator 13 can be utilized to operate the ring rail while the wheel 27 is making only a partial revolution. If it is desired to wind on the bobbin or yarn receiver a preliminary winding of considerable size, I propose to use a construction such as illustrated in Fig. 3 wherein the disengaging member 50 is mounted on a shaft 51 journaled in a bracket 52, which shaft has thereon a gear 53 that meshes with and is driven by a pinion 54 rigid with the ratchet wheel 27 with which the pick-pawl 28 engages. By using gears 53, 54 of proper sizes, it is possible to provide a construction whereby the ratchet 27 may make several revolutions before the disengaging member 50 is brought into operative position.

30 In the embodiment illustrated in Fig. 3 the disengaging member 50 is returned to its normal initial position by means of a spring 58 similar to the spring 40 in Fig. 2, one end 35 of the spring being connected to the bearing of the shaft 50 and the other to the gear 53. The gear 53 is provided with a stop projection 56 which engages a stop member 57 carried by the bracket 52, said stop projections 40 limiting the return movement of the member 50. Fig. 3 shows the parts in position for operation. As the actuator 13 vibrates the ratchet 27 is rotated in the direction of the arrow thereon, and through the gears 54, 53 45 the disengaging member 50 is rotated in the direction of the arrow. When the member has made a successive complete rotation it engages the finger 59 extending from the actuator 13 and lifts said actuator out of 50 engagement with the rocker member 5, and during this movement the pawl 28 is 55 disengaged from the ratchet 27 by the parts 33, 35. In other respects the device shown in Fig. 3 is similar to that shown in Figs. 1 and 2.

While I have herein illustrated some selected embodiments of my invention, I do not wish to be limited to the constructional features shown.

60 I claim:

1. In a machine of the class described, the combination with a ring rail, of an actuating mechanism to give the ring rail a traversing movement to effect the laying of a preliminary winding on a yarn receiver, an-

other actuating mechanism operable from an instrumentality independent from that which operates the first-named mechanism to give the ring rail a traversing movement to lay a main or service winding, and means 70 automatically to render inoperative the first-named actuating mechanism when the preliminary winding is completed.

2. In a machine of the class described, the combination with a ring rail, of an actuating mechanism to give the ring rail a traversing movement to effect the laying of a preliminary winding on a yarn receiver, another actuating mechanism operable from an instrumentality independent from that which operates the first-named actuating mechanism to give the ring rail a traversing movement to lay a main or service winding, and means automatically to render inoperative the first-named actuating mechanism 85 when the preliminary winding is completed, said first-named mechanism having provision for varying the size of the preliminary winding.

3. In a machine of the class described, the combination with a ring rail, of an actuating mechanism to give the ring rail a traversing movement to effect the laying of a preliminary winding on a yarn receiver, another actuating mechanism operable from an 95 instrumentality independent from that which operates the first-named actuating mechanism to give the ring rail a traversing movement to lay a main or service winding, and means automatically to render inoperative the first-named actuating mechanism when the preliminary winding is completed, said first-named mechanism having provision for varying the position of the preliminary winding on the yarn receiver. 100

4. In a machine of the class described, the combination with a ring rail, of an actuating mechanism to give the ring rail a traversing movement to effect the laying of a preliminary winding on a yarn receiver, another actuating mechanism operable from an instrumentality independent from that which operates the first-named mechanism to give the ring rail a traversing movement to lay a main or service winding, and means 110 automatically to render inoperative the first-named actuating mechanism when the preliminary winding is completed, said first-named mechanism having provision for varying both the size and the position on the 115 yarn receiver of the preliminary winding.

5. In a device of the class described, the combination with a ring rail, of an actuating mechanism to give said ring rail a comparatively rapid traversing movement to effect the laying of a preliminary winding on a yarn receiver, another actuating mechanism operable from an instrumentality independent from that which operates the first-named mechanism to give the yarn receiver a 125

65 preliminary winding on a yarn receiver, an- 130

slower traversing movement to lay a main or service winding, and means automatically to render inoperative the first-named actuating mechanism when the preliminary winding is completed.

6. In a device of the class described, the combination with a ring rail, of a builder motion to give said ring rail a traversing movement to wind a main or service winding on a yarn receiver, a preliminary winding mechanism operable from an instrumentality independent from that which operates the builder motion for giving the ring rail a traversing movement to wind a preliminary winding, and means automatically to render inoperative said preliminary winding mechanism when the preliminary winding is completed.

7. In a device of the class described, the combination with a ring rail, of a builder motion to give said ring rail a traversing movement to wind a main or service winding on a yarn receiver, a preliminary winding mechanism operable from an instrumentality independent from that which operates the builder motion for giving the ring rail a traversing movement to wind a preliminary winding, and means actuated by the preliminary winding mechanism to render it inoperative when the preliminary winding is completed.

8. In a machine of the class described, the combination with a ring rail, of an actuating mechanism to give the ring rail a traversing movement to effect the laying of a preliminary winding on a yarn receiver, another actuating mechanism operable from an instrumentality independent from that which operates the first-named mechanism to give the ring rail a traversing movement to lay a main or service winding, and means actuated by said first-named mechanism to render it inoperative when the preliminary winding is completed.

9. In a device of the class described, the combination with a ring rail, of two devices actuated from independent instrumentalities, one of which operates to give the ring rail a traversing movement for winding a preliminary winding on a yarn receiver and the other of which gives said ring rail a traversing movement for winding a main or service winding on a yarn receiver, and means for automatically rendering the first-named device inoperative when the preliminary winding is completed.

10. In a device of the class described, the combination with a ring rail, of two devices actuated from independent instrumentalities, one of which operates to give the ring rail a traversing movement for winding a preliminary winding on a yarn receiver and the other of which gives said ring rail a traversing movement for winding a main or service winding on a yarn receiver, and

means actuated by the first-named device to render it inoperative when the preliminary winding is completed.

11. In a machine of the class described, the combination with a ring rail, of an actuating mechanism to give the ring rail a traversing movement to effect the laying of a preliminary winding on a yarn receiver, another actuating mechanism adapted to be driven independently of the first-named mechanism to give the ring rail a traversing movement to lay a main or service winding, and means actuated by the first-named actuating mechanism to render it inoperative upon the completion of the preliminary winding, said first-named mechanism having provision for varying the size of the preliminary winding and its position on the yarn receiver.

12. In a machine of the class described, the combination with a ring rail, of an actuating mechanism to give the ring rail a traversing movement to effect the laying of a preliminary winding on a yarn receiver, another actuating mechanism adapted to be driven independently of the first-named mechanism to give the ring rail a traversing movement to lay a main or service winding, and means actuated by the first-named actuating mechanism to render it inoperative upon the completion of the preliminary winding, said first-named mechanism having provision for varying the size of the preliminary winding.

13. In a machine of the class described, the combination with a ring rail, of an actuating mechanism to give the ring rail a traversing movement to effect the laying of a preliminary winding on a yarn receiver, another actuating mechanism adapted to be driven independently of the first-named mechanism to give the ring rail a traversing movement to lay a main or service winding, and means actuated by the first-named actuating mechanism to render it inoperative upon the completion of the preliminary winding, said first-named mechanism having provision for varying the position of the preliminary winding on the yarn receiver.

14. In a device of the class described, the combination with a ring rail, of a builder arm to give said ring rail a traversing movement to wind a main or service winding on a yarn receiver, means for actuating said arm, a preliminary winding actuator operable independently of the builder arm for giving the ring rail a traversing movement to wind a preliminary winding, and means actuated by said actuator to render it inoperative when the preliminary winding has been completed.

15. In a device of the class described the combination with a ring rail, of a builder motion including a builder chain, a builder arm connected to the chain and means for

actuating the arm to give said ring rail a traversing movement to wind a main or service winding on a yarn receiver, a preliminary winding actuator constructed to transmit motion to said ring rail independently of said builder chain for giving said ring rail a traversing movement to wind a preliminary winding and means actuated by said actuator to render it inoperative when the preliminary winding has been completed.

16. In a device of the class described the combination with a ring rail of a builder arm, a rocker operable thereby, connections between said rocker and the ring rail, a continuously-moving actuator operable independently of the builder arm, detachably connected directly to the rocker for actuating the latter, and means actuated by the movement of the actuator to disconnect it from the rocker after a predetermined time.

17. In a device of the class described, the combination with a ring rail, of a rocker member by which the ring rail is actuated, a continuously-reciprocating actuator having a notch to engage said rocker, a disengaging member, and means to actuate the latter by movement of the actuator thereby to disconnect the latter from the rocker.

18. In a device of the class described the combination with a ring rail of a builder arm, a rocker operable thereby, connections between the rocker and the ring rail, a continuously moving actuator, operable independently of the builder arm, detachably connected directly to the rocker, an adjustable disconnecting member and means to actuate the latter by movement of the actua-

tor after a predetermined time to effect the disengagement of the actuator from the rocker.

19. In a device of the class described, the combination with a ring rail, of a rocker member for actuating the latter, a continuously-moving actuator detachably connected to the rocker member, a rotary-disengaging member for disengaging the actuator from the rocker member, a ratchet associated with said disengaging member, and a pawl carried by the actuator for operating the ratchet and thereby actuating the actuating member to effect disengagement of the actuating member from the rocker member.

20. In a device of the class described, the combination with a ring rail, of a rocker member for actuating the latter, a continuously-moving actuator detachably connected to the rocker member, a rotary-disengaging member for disengaging the actuator from the rocker member, a ratchet associated with said disengaging member, a pawl carried by the actuator for operating the ratchet and thereby actuating the actuating member to effect disengagement of the actuating member from the rocker member, and means to render the pawl inoperative when the actuator is disengaged.

In testimony whereof, I have signed my name to this specification, in the presence of two subscribing witnesses.

WINTHROP PARKER.
